UNITED STATES PATENT OFFICE.

GEORGE WIARD, OF BATAVIA, NEW YORK, ASSIGNOR TO THE WIARD
PLOW COMPANY, OF SAME PLACE.

MOLD FOR CASTING CHILLED MOLD-BOARDS.

SPECIFICATION forming part of Letters Patent No. 231,877, dated August 31, 1880.

Application filed December 2, 1879.

To all whom it may concern:

Be it known that I, GEORGE WIARD, of Batavia, in the county of Genesee and State of New York, have invented a new and useful Improvement in Molds for Casting Chilled Mold-Boards, of which the following is a specification, reference being had to the accompanying drawings.

My invention relates more particularly to the construction of the chill which forms one side of the mold in which the mold-board is cast, and also to the construction of the flask or frame of the mold.

Chills as ordinarily used in casting mold-boards consist of a flat plate of iron, which is secured to the flask so as to form the outer side of the mold. The hot metal enters the mold at the bottom and rises in the mold until the same is filled. The chill is subjected at the point where the liquid enters the mold to the heating action of the current of hot molten metal, while those parts of the chill which are farther removed from the point at which the hot metal enters the mold become less heated, because the metal when it reaches those parts has become considerably cooled by contact with the chill. In this manner the chill is unequally heated and becomes warped, thereby changing the form of the mold and producing castings of unequal thickness, and eventually resulting in the cracking and final destruction of the chill. The unequal heating of the chill also causes an unequal chilling or hardening of the casting, because the highly-heated portions of the chill near the point at which the metal enters do not permit the casting to cool as quickly as the less-heated portions near the extremities of the chill.

The object of my invention is to remedy these difficulties; and it consists in constructing the chill thickest at the point where the molten metal enters the mold and gradually decreasing the thickness of the chill from that point toward its extremities.

In the accompanying drawings, consisting of two sheets, Figure 1 is an elevation of a mold with the chill-plate removed. Fig. 2 is a vertical section in line xx , Fig. 1. Fig. 3 is a section in line yy , Fig. 1. Fig. 4 is an elevation of the mold with the chill-plate ap-

plied thereto. Fig. 5 is a section in line zz , Fig. 1.

Like letters of reference refer to similar parts in the several figures.

A represents the flask or frame of the mold, 55 and B that portion of the mold which is composed of sand rammed into the flask.

C represents the pattern of the mold-board; d , the gate or opening at which the metal enters the bottom of the mold, and e the passage or channel into which the metal is poured. 60

F is the chill-plate, provided on its upper and lower sides with stiffening-ribs g , and fitting against the open-face side of the flask, to which it is fastened by clamps h and wedge-keys i . 65

The chill-plate is constructed thickest opposite the gate d where the molten metal enters the mold, and its thickness decreases from that point in all directions toward the extremities of the mold. For casting a mold-board of ordinary size the chill is made opposite the gate d about three inches thick, and its thickness is gradually reduced in all directions toward the edges of the mold, 70 where the chill is made about three-quarters of an inch thick. The molten metal entering the mold through the gate d first comes in contact with the thickest portion of the chill, and as the metal rises and spreads in the mold and loses a portion of its heat it comes 75

in contact with successively-thinner portions of the chill-plate. As the capacity of the chill-plate for absorbing heat is in proportion to its thickness, the thicker portion, which is exposed to contact with the hottest metal, and the thinner portions, which are acted upon by the partially-cooled metal, are uniformly heated. By this means the warping of the chill-plate and the consequent distortion of the mold, producing castings of unequal thickness, are prevented, and the castings are chilled to a uniform degree of hardness over their entire surface. 80

The metallic chill-plate F prevents the air and vapors which are generated and displaced by the molten metal entering the mold from being absorbed at the front side of the mold, the surface capable of absorption being confined to that portion of the mold which is formed of sand. 85

In order to provide a means of escape for the gases and vapors which are not absorbed by the sand, the upper bar of the flask A is provided on its face side with narrow vertical grooves *l*. After the pattern is molded in the flask the grooves *l* are continued in the face of the sand portion of the mold to the upper edge of the mold, as clearly shown in Fig. 1.

The grooves *l* and their continuations are preferably made about one-sixteenth part of an inch in width and depth. The small size of these grooves prevents the molten metal from entering the same, as the metal has become considerably cooled when it reaches the upper edge of the mold. The vapors and air

which are not absorbed by the sand are driven from the mold through the grooves *l*, thereby insuring castings which are free from air-holes.

I claim as my invention—

A metallic chill-plate for casting mold-boards and similar articles, made thickest at the point where the molten metal enters the mold, and made gradually decreasing in thickness toward the extremities of the mold in all directions, substantially as set forth.

GEORGE WIARD.
